CLAIM

The ornamental design for a video training device, as
shown and described.

DESCRIPTION

FIG. 1 is a top perspective view of a video training
device showing our new design;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a top plan view thereof; and

FIG. 7 is a bottom plan view thereof.

The stippled element under the screen in FIGS. 1, 3 and
6 represents a conventional speaker grill.

FIG. 1

FIG. 2

FIG. 3

FIG. 4
